UNITED STATES PATENT OFFICE

JOHN HARWOOD GANZER, OF DULUTH, MINNESOTA, ASSIGNOR TO DULUTH SHOW CASE COMPANY, OF DULUTH, MINNESOTA, A CORPORATION OF MINNESOTA

STEEL NAIL BIN

Application filed March 28, 1927. Serial No. 178,847.

This invention relates to novel and practical construction of steel nail bins which have a large storing capacity, which are light in construction and which are particularly adapted for use in hardware stores, store rooms and the like where large quantities of nails are stored or used and where a minimum amount of space only can be utilized for that purpose.

Heretofore nails have been stored in their original containers or kegs and placed on the floor which greatly detracted from the appearance of the store or room and which were troublesome to handle, or the nails were emptied into large and cumbersome bins which took up considerable space.

The present invention eliminates these disadvantages and its primary object is to provide an all metal nail bin formed from a single sheet of metal, which is light in construction, easily and economically manufactured, which is strong and durable and which is capable of being placed in racks and tiers to conserve the maximum amount of space.

A further object thereof is to provide a steel nail bin in which the nails may be easily and quickly emptied into from the ordinary container or keg in which they are usually shipped.

A further object thereof is to provide a steel nail bin which is manufactured from a single sheet of metal, which is rigidly braced, which will readily slide upon shelves or racks upon which they may be placed, and to allow ready access to the nails without pulling the bin from the rack or removing any covers.

Other objects and advantages will herein-after appear.

A preferred and practical embodiment of the bin is shown in the accompanying drawings in which

Fig. 1 is a front, perspective view of the improved bin.

Fig. 2 is a transverse section of the bin taken on line 2—2 of Fig. 1.

Fig. 3 is a section on the line 3—3 of Fig. 1 showing the improved handle attached to the front end of the box.

The invention comprises in general a bot-

tom 1 having the outer ends thereof extending upwardly to form a front end 2 and back 3, and sides 4 extending upwardly substantially at right angles to the bottom and formed integrally therewith.

The sides 4 have their ends bent inwardly and are attached to the back 3 by means of rivets 5. These sides have their bottom forward end inclined upwardly to coincide with the upwardly extending bottom to form a front 2.

These inclined ends have a portion thereof bent inwardly substantially at right angles to the sides and are fastened to the front in any suitable manner such as rivets 6.

The forward top edges of the bin are inclined downwardly to connect with the top edge of the front. The sides 4 and the back 3 have their top edges bent inwardly to form a smooth top surface and to further strengthen and reinforce the sides. The sides have panels 7 stamped therein to further strengthen the sides and add rigidity thereto.

Cross members 8 preferably formed of flat metal bars are bent to form downward extending legs 9 which are connected to the sides of the box. The lower end of each leg is riveted to the sides through the panels. Above the panels are inwardly projecting protuberances 10 formed on the top edges of the sides to form an attaching surface flush with the inside of the panel and to which the upper end of the leg is attached.

The bottom 1 as it extends upwardly and to form the back 3 is rounded as at 11 to enable the box to be more easily slid. The bottom 1 is also rounded at its front end where it extends upwardly and forwardly to form the front 2.

The bottom 1 is provided with grooves or corrugations 12 protruding upwardly from the bottom as clearly shown in Figs. 1 and 2, to further strengthen the box and to facilitate in sliding the box on the shelves or racks.

The lower edges of the box are also rounded as at 13 to enable the box to be slid in and out more readily.

The front has an integral edge 14 extending forwardly therefrom substantially at right angles thereto. This edge increases the

rigidity of the front and provides a smooth top surface therefor.

A handle 15 stamped from a single piece of metal is riveted to the front as clearly shown in Fig. 3. The bottom edge of the handle has an upwardly extending ledge 16 formed integrally with the handle. The edge 14 of the top and the ledge 16 of the handle form a recess 17 into which suitable distinguishing

means such as a card 18 may be inserted. This card may have notations thereon to designate the size and kind of nails which are stored in each of the several bins. The handle is rigidly secured to the front and has side members 19 to form a hand hold 20.

These boxes are generally stored in racks (not shown) and placed side by side and above each other in tiers. The front ends of the box may protrude outwardly from the racks at a line perpendicular to the beginning of the downwardly inclined edge of the side. Thus it is readily seen that the bins require but a minimum amount of space, that each bin is properly marked, and that easy access is provided for obtaining nails from the bins.

From the foregoing description it will be seen that a box is provided that is light in weight, strong and durable in construction, which occupies a minimum amount of space and contains improvements heretofore unknown.

It is apparent that changes in form, construction, and arrangement of parts may be made without departing from the spirit and without sacrificing the advantages of the invention and the right is reserved to make all such changes as may fairly fall within the scope of the following claim.

I claim:

In combination with a nail bin having a forwardly inclined front and a forwardly extending edge integral with said front and substantially at right angles thereto, of a handle stamped from a single piece of metal fixed to said front and comprising a front, side members integral with the front thereof to space said front from the front of the bin and forming a hand-hole, and an upwardly turned edge integral with the front of said handle and forming a recess between the forwardly extending edge of the bin and the upwardly turned edge, to receive a card, or the like, to designate the contents of the bin.

JOHN HARWOOD GANZER.
